UNITED STATES PATENT OFFICE.

WARREN B. SIMPSON, OF HUNTINGDON, PENNSYLVANIA.

INSULATOR-BRACKET.

1,378,140.

Specification of Letters Patent. Patented May 17, 1921.

Application filed November 25, 1919. Serial No. 340,452.

To all whom it may concern:

Be it known that I, WARREN B. SIMPSON, a resident of Huntingdon, county of Huntingdon, and State of Pennsylvania, have invented certain new and useful Improvements in Insulator-Brackets, of which the following is a specification.

My invention relates to insulator brackets and more especially to that type which is adapted to be secured to the top or roof of a pool for carrying the wires.

The object of my invention is to construct a bracket of the character above indicated which is most simple in construction and at the same time having great strength and rigidity, ease of securing the same to the pole, and cost of production reduced to a minimum.

A further object of the invention is to construct and arrange the parts of the bracket so that the wires supported by the bracket are close to the line of the bolt holes or fastening means, thereby further assisting in preserving the shape of the bracket and its adjusted position under all conditions of use and weather after being secured to the pole.

Another object of the invention is to form and arrange the portion of the bracket in contact with the pole to be easily and quickly placed in proper position on the top of a pole and at the same time permit the bracket to readily adjust itself to the angle of the roof of the pole top while being fastened or secured thereto.

Other objects and advantages of the invention will appear from the detailed description, manner of assembling and applying the same to be hereinafter given.

The invention consists of structural characteristics and relative arrangements of elements which will be hereinafter more fully described and particularly pointed out in the appended claims.

In the drawings, in which similar reference characters indicate the same parts in the several figures,

Figure 1 is a side elevation of the improved bracket in position on top of a pole;

Fig. 2 is an end view;

Fig. 3 is a top plan view.

In the drawings 10 and 11 represent two sections of metal preferably of channel iron form and made of different lengths, the section 10 as shown being shorter than 11. Said sections 10 and 11 are bent at an angle and

placed back to back and firmly secured together by rivets 12 or other suitable means so as to form an upright central standard 13 and two oppositely disposed and diverging sections 14 and 15 which form preferably a right angle with each other as illustrated. The outer ends 16 and 17 of said sections 14 and 15 are turned or bent upwardly toward the standard 13 and arranged parallel with the same for purposes to be presently described. The longer section 11 extends above and beyond the upper end of the short section 10 to form an upper reduced end 18. Each of the outer ends 16 and 17 and upper reduced end 18 are provided with any one of the commonly used attachments or means of fastening insulators I to the bracket.

Each of the diverging sections 14 and 15 has one or more holes 21, drilled in the web portion of the channel through which lag bolts 22 or other fastening devices are passed to firmly and rigidly secure the bracket to the top of a pole P which has had its top roofed off as is usual in poles designed for supporting and carrying electric conductors and the angle of the roof comb at top of the pole corresponds to the angle between the diverging sections 14 and 15 of the bracket.

From the foregoing disclosure of construction and arrangement of the parts of the invention it will be seen that the bracket consists primarily and essentially of only two simple elements 10 and 11 which are capable, owing to their channel cross-sections, of not only rigidly supporting the weight of the electric conductors but also at the same time resisting any strains in the directions parallel to the length of the electric conductors supported by the bracket, or any angle thereto. Furthermore the diverging sections 14 or 15 of the bracket coming in contact and secured to the top of the pole readily adapt themselves to the angle of the pole top while being screwed or forced down on the pole, thereby insuring a maximum resistance against any movement whatsoever. The two simple elements 10 and 11 of the bracket also enable these conductors to be supported as near as possible to the points of attachment of the bracket and hence reduces to a minimum the lever arms of the forces acting in the conductors from the points of attachment of the bracket and hence the factor of safety in preventing the bracket from being detached from the pole or its shape distorted is a maximum, con-

sidering the number of elements and amount of metal employed in the manufacture of said bracket. The provision of having one section 11 longer than section 10 enables me 5 to readily without any further machining operations to provide a reduced end 18 on which the upper insulator holding means can be formed, thus producing a bracket at the lowest cost with a maximum number of 10 insulator supports within a given area and capable of being employed for conductors conveying high voltages.

From the herein described constructions taken in connection with the accompanying 15 drawings, it will be manifest that a bracket such as disclosed will fulfil all the necessary requirements of such devices and fully and efficiently carry out all the functions and advantages pointed out in the statement of 20 the invention, and it will be readily understood that various minor changes in the specific details of construction can be resorted to within the scope of the claims without departing from, or sacrificing any of the advantages 25 of the present invention.

What I claim is:—

1. An insulator bracket to be secured to the top of a pole comprising two sections of channel iron of unequal length bent at an 30 angle and connected together at a portion of the back of their web lengths to form a central upright standard provided with means on the outer end of the longer section for engaging an insulator, the disconnected 35 portions of the two sections diverging from

each other and so constructed, arranged and adapted to have the back of their web lengths to be seated and secured to the top of a pole and provided at each of their oppositely disposed ends with means for engaging an insulator. 40

2. An insulator bracket of substantially anchor shape comprising two sections of channel iron bent at an angle and arranged back to back and connected together at a portion of their lengths to form a central upright standard having means at its end for engaging an insulator, the disconnected portions of the two sections diverging from each other and so constructed, arranged and 45 adapted to be seated and secured to the top of a pole and provided at each of their ends with means for engaging an insulator. 50

3. An insulator bracket of substantially anchor shape comprising two sections of channel iron of unequal length bent at an angle and arranged back to back and connected together at a portion of their lengths to form a central upright standard having means on the outer end of the longer section 55 for engaging an insulator, the disconnected portions of the two sections diverging from each other and so constructed, arranged and adapted to permit the web sections of the channels to be seated and secured to the top of a pole and provided at each of their ends with means for engaging an insulator. 60 65

In testimony whereof I affix my signature.

WARREN B. SIMPSON.
